CONNECTING PIECE FOR A CHAIR ARM
OR THE LIKE

Forest Wilson, P.O. Box 6, Medinah, Ill.

Filed Feb. 24, 1959, Ser. No. 54,723

Term of patent 14 years

(Cl. D15—8)

Fig. 1 is a perspective view of the connecting piece for a chair arm or the like embodying my new design;

Fig. 2 is a side elevational view;

Fig. 3 is a front elevational view; and

Fig. 4 is a top plan view.

The broken line showing portions of a chair arm and leg is for illustrative purpose only.

I claim:

The ornamental design for a connecting piece for a chair arm or the like, substantially as shown and described.
